UNITED STATES PATENT OFFICE.

EUGÈNE ROPP, OF BESANCON, FRANCE.

PIPE.

Application filed September 6, 1922. Serial No. 586,505.

To all whom it may concern:

Be it known that I, EUGÈNE ROPP, a citizen of the Republic of France, and residing at Besançon, Doubs Department, Rue des Villas, in the Republic of France, industrial, have invented certain new and useful Improvements in Pipes, of which the following is a specification.

My invention relates to pipes whereof the 10 stem contains a filter secured to the mouthpiece and extending into the bottom of the bowl.

The said filter is constituted by a tube of thin metal with perforated walls for the 15 passage of the smoke.

One feature of this invention is that the said filter, at the end situated within the bowl, is closed at the top so as to prevent ashes or fragments of tobacco from falling 20 through the smoke holes. Another feature is that the filter is given a certain size and shape with respect to the inner chamber of the stem so that it may be obliquely situated in said chamber upon separating the mouth- 25 piece from the stem, so as to be used to give an effective scraping to the walls of said chamber as far as the end of the same.

Should the said chamber be cylindrical and connected with the bowl by a narrow 30 passage, the filter will preferably comprise a cylindrical portion extending through said passage and a conical part whereof the small base is joined to said cylindrical part, and the large base surrounds the inner end 35 of the mouthpiece. The filter is preferably secured to the mouthpiece by a screw joint or bayonet joint. One particular feature of this invention consists in constructing the joint in an economical manner by forming 40 on the filter a boss extending inwardly or outwardly and slidably in a helical groove formed around the end of the mouthpiece or within the latter.

When the filter is assembled by screwing 45 it to the mouthpiece, care should be taken that when screwed up, the solid part of the filter shall be in the top position or towards the interior of the bowl. One feature of the invention consists in providing 50 on the filter a ring or shoulder fitting against the end of the mouthpiece whereby the screwing is limited to the exact point required.

The accompanying drawing given by way 55 of example shows two embodiments of this invention.

Fig. 1 is a lengthwise section of a pipe (indicated in dotted lines) showing the filter in section and the mouthpiece in elevation.

Fig. 2 is a plan view of the top part of 60 the filter alone.

Fig. 3 is a lengthwise section of a second form of construction.

Fig. 4 is a plan view of the separate 65 filter.

In Figs. 1 and 2, 1 indicates the filter consisting of a cylindro-conical tube whose rear end is disposed upon the mouthpiece 2 whilst the front end extends within the bottom of the bowl 3 wherein it opens by 70 two apertures 4; said tube is further provided with a plurality of lateral orifices 5 situated near the mouthpiece. The said tube is secured by means of a helical groove 6 in the mouthpiece and a boss 7 formed on 75 the tube; upon screwing the latter, its end makes contact with a shoulder 8 at the end of the mouthpiece, the tube being so arranged that the orifices 4 will now come into the lateral position. In this manner the 80 front end of the tube will have a solid part 9 at the top for retaining the ashes and fragments of tobacco so that only the smoke is allowed to pass through the orifices 4.

Should it be desired to obtain a double ex- 85 pansion of the smoke in the filter, to the tube 1 may be added a perforated inner tube which also fits upon the mouthpiece.

It will be observed that upon removing the mouthpiece from the stem, the filter can 90 be inserted obliquely into the latter so that its end can be used to give an effective scraping to the inner wall of the chamber 10 of the tube as far as the end of the same.

In the modified form of construction shown in Figs. 3 and 4, the filter 1 consists of a tube secured to the mouthpiece and having at the periphery a plurality of small orifices 5 as well as two larger apertures 4 100 opening into the bottom of the bowl 3.

The rear end of the tube 1 is provided with a stud 7 engaging one of the helical grooves 6 formed in the bore of the mouthpiece 2.

The screwing movement is limited by a ring 11 mounted on the tube and affording a well-defined position of the tube on the mouthpiece so that the two apertures 4 assume the lateral position and the solid part 110 9 is at the top when the mouthpiece occupies the normal position.

Claims:—

1. A pipe comprising a bowl, a stem forming one part with the bowl, a mouthpiece secured in a removable manner to this stem, a 5 tubular part connected with this mouthpiece and extending into the lower part of the bowl, this tubular part being laterally perforated at its middle portion within the stem so as to provide several holes which act 10 as a filter, said tube being terminated by a cylindrical portion extending into the bottom of the bowl and being used for the draught.
2. A pipe comprising a bowl, a mouthpiece removably attached to said bowl, a tube with apertured walls secured to said mouthpiece and extending within the lower part of said bowl, the top of the end portion of said tube being solid in order to 15 prevent the ashes from falling directly through the apertures in the walls.
3. A smoking pipe comprising a bowl, a stem made in one part with the said bowl and provided internally with a chamber 20 communicating with the bottom of said bowl through a conduit of a small diameter, a removable mouth-piece provided upon the said stem, a tubular member comprising a cylindrical part engaged into the said conduit of 25 a small diameter and a truncated part entering into said chamber of the stem, the said cylindrical part being closed at its end and having two lateral openings leading into 30

the bottom of the bowl, and the said truncated part having orifices provided in its 85 walls and having its larger basis secured upon the mouth-piece.

4. A pipe comprising a bowl, a mouthpiece removably secured to said bowl, a pipe 40 stem integral with said bowl, said pipe stem comprising a cylindrical chamber and a passage of smaller diameter opening into said bowl, a tube with apertured walls secured to said mouthpiece and extending within the lower part of said bowl a ring 45 disposed upon said tube and adapted to enter into contact with the end of said mouthpiece, a non-apertured portion at the end of said tube, said ring being so disposed that the said tube screwed into the mouthpiece 50 is enabled to assume a position such that the said non-apertured portion shall be situated exactly at the top, thereby preventing the ashes from falling into said tube.

5. A pipe comprising a bowl, a mouthpiece removably secured to said bowl, a pipe 55 stem integral with said bowl, a tube with apertured walls secured to said mouthpiece, said tube being attached by screwing, a boss formed upon the tube by pressing the wall 60 of said tube, a helical groove formed at the end of said mouthpiece and cooperating with said boss.

In testimony, that I claim the foregoing as my invention I have signed my name.

EUGÈNE ROPP.
